CLAIM

The ornamental design for a cribbage board, as shown and described.

DESCRIPTION

FIG. 1 is a top plan view of a cribbage board showing my new design;

FIG. 2 is a front elevation thereof; the rear elevation being a mirror image thereof;

FIG. 3 is a right side elevation thereof;

FIG. 4 is a left side elevation thereof; and

FIG. 5 is a bottom plan view thereof.

*FIG. 1**FIG. 2**FIG. 3**FIG. 4**FIG. 5*
